UNITED STATES PATENT OFFICE.

LUCIAN W. BUGBEE, OF SOUTHBIDGE, MASSACHUSETTS, ASSIGNOR TO AMERICAN OPTICAL COMPANY, OF SOUTHBIDGE, MASSACHUSETTS, A CORPORATION OF MASSACHUSETTS.

LENS.

1,199,343.

Specification of Letters Patent. Patented Sept. 26, 1916.

Application filed July 23, 1915. Serial No. 41,484.

To all whom it may concern:

Be it known that I, LUCIAN W. BUGBEE, a citizen of the United States, residing at Southbridge, in the county of Worcester 5 and State of Massachusetts, have invented certain new and useful Improvements in Lenses, of which the following is a specification.

This invention relates to lenses having a multiplicity of foci, and is adapted primarily as a corrective lens for the vision, although it may be used and found equally efficient for other purposes as well.

The principal object of the invention is to provide a lens having a distance portion, a reading portion and an intermediate portion, and to so form the lens as to arrange the distance portion at the upper part of the lens in the field of general vision, the intermediate portion at the lower part of the lens as the desirable position for use in going up or down steps or the like, and the reading portion between the aforementioned portions so as to relieve the necessity of casting the head or eyes to an unnatural position when reading, as has been the previous common practice.

Another object is to provide a multi-focal lens composed of but two parts, thereby providing a lens of this character in which the cost of manufacture will not be appreciably increased over the cost of manufacture of the ordinary bifocal form of lens.

Another object is to provide a multi-focal lens in which but one of the blanks composing the lens has a different index of refraction from the remaining blanks, thus obviating the necessity of the provision of other than the ordinary crown and flint forms of glass.

With the foregoing and other objects in view the invention consists in the novel features of construction, combination and arrangement of parts as will be hereinafter more fully described, illustrated in the accompanying drawings and claimed.

In the drawings: Figure I is a sectional view through a two piece multi-focal lens constructed in accordance with the invention. Fig. II is a similar view through a slightly modified form of lens. Fig. III is a face view of either of the structures illustrated in Figs. I and II.

Referring to the drawings by numerals,

particularly to Fig. I, wherein is illustrated a preferred embodiment of my invention, 1 designates a lens blank which has fused into a recess formed in one face thereof a segment 2, the material of the segment having, as is usual, a different index of refraction from the blank 1. These blanks may be of the ordinary construction commonly used in the manufacture of bifocal lenses, and may be united in any preferred manner.

As shown the segment is arranged upon the outer face of the blank 1, to one side thereof, and extends inwardly of the blank a distance approximately one-half the width 70 of the blank. In the formation of the improved multi-focal lens the outer or convex faces of the blank and segment are ground to any desired corrective curve, as shown at 3. So far the lens is of the same 75 form as is commonly used in the manufacture of bifocals, the only difference being that the segment 2 is relatively larger than ordinarily used.

Upon the inner or concave face of the blank 1 a curve 4 is ground, obliquely to the curve of the inner face of the blank so as to include approximately one-half of the segment 2. It will thus be seen that all of the material of the blank 1 is cut away 85 from the blank 2 at its lower portion and that the inner face of the blank 2 is formed into a curve corresponding with the curve formed upon the inner face of the blank 1.

As before stated, the blank 2 is of a different index of refraction from the blank 1 and, therefore, the curves of the two blanks being the same it will be understood that each of the blanks will have different focal powers, the segment 2 usually being of a higher index of refraction than the blank 1 and, therefore, the lower portion of the blank 2 will be of a slightly higher focal power than the blank 1.

The curved fused connection between the blanks 1 and 2, together with the difference in refractive index between the two blanks serves to provide a relatively strong lens throughout the extent of their fused connection. It will thus be seen that the distance 100 between *a* and *b* in Fig. I will be the distance portion of the lens; the distance between *b* and *c* will be the reading portion, or strongest portion of the lens, and the distance between *c* and *d* will be the intermediate or the 110

difference in refractive index between the two parts of the lens, the curve 4 being ground into the segment 2 throughout approximately one-half its length so that the distance between *b* and *c* and *c* and *d* will be substantially equal.

In Fig. II of the drawings I have illustrated another manner in which a trifocal lens may be formed having the reading portion arranged between the distance and intermediate portions. This lens comprises a blank 1' and a segment 2' which are of the same construction as set forth in connection with Fig. I of the drawings. Instead of 10 grinding the lens as set forth in connection with Fig. I, however, a recess 5 is formed in the segment 2 at the lower portion thereof, and this recess has fused therewith a second segment 6 which may be of the same or of a 15 different index of refraction from the blank 1, the fusing of the blank 5 into the segment 2 serving to provide an intermediate portion at the lower part of the lens while the reading portion will be arranged between the intermediate and the distance portions, as will 20 be understood.

It is thought that the construction and advantages of the improved lens will be readily apparent to those skilled in the art to which 25 the invention appertains, and while I have herein shown and described certain specific manners of accomplishing the result desired I do not wish to be limited thereto except to such limitations as the claims may import.

30 I claim:

1. A multi-focal lens including a distance portion, a reading portion and an intermediate portion, said reading portion being ar-

35 ranged between the distance portion and the intermediate portion.

2. An ophthalmic lens including a distance portion, a reading portion and an intermediate portion, the intermediate portion being arranged at the lowermost portion of the lens, the distance portion being arranged 40 at the uppermost portion of the lens, and the reading portion being arranged between the intermediate and distance portion.

3. A lens comprising a blank having a recess formed therein, a segment fused in said 45 recess, the face of the lens opposite to said segment being ground away to expose a portion of the segment.

4. A trifocal lens formed from two pieces 50 of glass of different indices of refraction and comprising an upper portion of one index, a lower portion of a different index, and an intermediate portion formed by overlapping the material of the upper and lower portions.

5. A trifocal lens formed from two pieces 55 of glass of different indices of refraction and comprising an upper portion of one index, a lower portion of a different index, and an intermediate portion formed by overlapping 60 the material of the upper and lower portions, one of said portions having a concave recess formed in the overlap thereof and the other portion having a convex surface fitting in the recess.

In testimony whereof, I affix my signature in presence of two witnesses.

70 LUCIAN W. BUGBEE.
